DRYING MACHINE

Ralph C. Parkes, Glenside, Pa.

Application March 14, 1946, Serial No. 654,376

5 Claims. (Cl. 34—222)

1

My invention relates to a drying machine of the type in which the material to be dried is moved through a chamber and subjected to a stream of heated air, or other fluid-drying medium, during its progress through said chamber.

One object of the invention is to produce an improved drying machine of the type set forth.

A further object is to produce improved means for regulating the distribution of the drying medium through the drying chamber to insure uniform drying of the material, regardless of the nature of the material, the moisture content thereof, the location of the material within the chamber, or its remoteness from or its proximity to the source of the drying medium.

A still further object is to produce an improved structure and assembly whereby the efficiency of the means for propelling the drying medium through the machine is increased.

A still further object is to produce an improved arrangement of the drying medium propelling means relative to the material to be dried whereby the flow of the drying medium to, and through, the drying chamber and over the material to be dried is improved.

A still further object is to produce improved means for accomplishing the foregoing objects with minimum alteration of, or interference with, the structure of the drying machine proper and at minimum cost.

These and other objects are attained by my invention as set forth in the following specification and illustrated in the accompanying drawings, in which:

Fig. 1 is a view, partly in side elevation and partly in section, of a drying machine embodying my invention;

Fig. 2 is an elevational view, looking in the direction of line 2—2 on Fig. 1, showing certain details of construction;

Fig. 3 is a view, partly in section and partly in elevation, taken on line 3—3 of Fig. 1;

Fig. 4 is an enlarged, fragmentary, top plan view, looking in the direction of line 4—4 on Fig. 3;

Fig. 5 is an enlarged, fragmentary view, similar to Fig. 2, showing an adjusting mechanism forming part of the structure and not shown in the other figures;

Fig. 6 is an enlargement of the upper portion of Fig. 3, better to show details of construction;

Fig. 7 is a fragmentary view, partly in section and partly in elevation, showing certain parts of the machine in one position thereof; and

2

Fig. 8 is a view, similar to Fig. 7, showing the same parts in another position thereof.

In Fig. 1 of the drawings, there is shown a drying machine including a housing built of heat-insulated walls defining a chamber through which the material to be dried is propelled while being subjected to the action of a fluid drying medium, such as heated air.

As illustrated, the machine is provided with an endless sprocket chain 10 which carries spaced poles 11 on which the sheet material to be dried is festooned in loops, the chain being carried and propelled by sprockets 12, at least one of which is driven by a source of power (not shown). It will be understood that, instead of poles 11 on which sheet material is festooned, the sprocket chains may carry and propel trays or other receptacles containing other types of material to be dried.

As will be seen from Figs. 1, 3 and 6, the machine illustrated is adapted to dry two separate pieces of sheet material 13 and 14 which are fed into the machine by suitably arranged and propelled feed rolls 15 and 16 which are driven by a belt or the like 17, operatively connected to a source of power, not shown. The pieces of sheet material are festooned in loops on the poles 11 and, between them, they occupy substantially the entire width of the machine. The poles 11 are provided with end gears 18 which engage racks 19 so that the poles rotate about their axes while moving between the feed and delivery ends of the machine. At the delivery end of the machine, there is provided a suitable driving and driven roll arrangement by means of which the dried pieces 13 and 14 are delivered to take-up rolls 20. Since this driving mechanism may be of any well-known structure, it is not shown or described in detail.

To a machine such as that above described, it has been known to add adjustable shutters such as those shown in Figs. 7 and 8, said shutters being assembled in separate sets A and B, one disposed above the piece of material 13 and the other above the piece of material 14. Provision was also made to adjust said sets of shutters independently of one another so as to regulate the amount of heated air to be directed against either of the pieces 13 and 14. As will be best seen from Figs. 7 and 8, the shutters referred to consist of fixed, spaced slots 23 and movable slats 24, the latter being carried by an arm 25. This arrangement which is now well known in the art is such that, if the arm 25 is moved to the left, as viewed in Fig. 6, the slats 24 are moved to the position

shown in Fig. 8, in which they at least partly obstruct the spaces between the fixed slats 23. If the arm 25 is moved to the right, the slats 24 assume the position shown in Fig. 7, in which the spaces between the fixed slats 23 are unobstructed. The movable slats 24 can, if desired, be arranged completely to obstruct the spaces between the fixed slats 23 instead of only partly obstructing said spaces, as shown in Fig. 8.

In addition to the adjustable shutters, it also has been known to provide fixed spaced slats 26, Fig. 3, which form a perforated floor 27 below the material to be dried and provide exit passages for the air blown downwardly over the pieces of fabric 13 and 14.

The heated air is blown over the materials to be dried by blowers 28, the discharge sides of which are connected by means of a passage 30 to an air-receiving space 31 above the material to be dried, and the intake sides of which are connected by a passage 32 to a compartment 33 located below the false floor 27 and enclosing heating coils 29. The flow of air from the compartment 33 into contact with the material to be dried, is regulated by the adjusting sets of shutters A and B.

In order better to control and regulate the flow of heat air over the material to be dried, I provide a baffle 34 which is arranged for joint movement with the movable slats 24 of the set of shutters A. As will be seen from the drawings, the set of shutters A is adjacent the air inlet 30 while the set of shutters B is remote from the air inlet. The baffle 34 is pivoted at its base to a fixed support 35 so as to be rotatable about a horizontal axis, in clockwise direction to the position shown in solid lines, or to the position shown in broken lines in Fig. 6. The baffle is so connected to the bar 25 carrying the movable slats 24 of the shutters A that, when the baffle is in its solid line position, in Fig. 6, the slats assume their vertical, non-obstructing position of Fig. 7, and when the baffle is moved to or toward its broken line position, the movable slats 24 move to, or towards, their slanted, obstructing position of Fig. 8.

Specifically, the baffle 34 is provided with a tab 37 which is pivoted to one end of an arm 38, the other end of which is pivoted to a link 39 mounted on a shaft 40 rotatably carried by the framework of the machine. The adjacent end of the arm 25 which actuates the shutters A is pivoted to a link 41 which is also mounted on the shaft 40. By this interlocking arrangement, when the baffle is rotated in clockwise direction, the arm 25, controlling the shutters A, is moved to the right, and the movable slats 24 of the shutters A are moved to their vertical, non-obstructing position, Fig. 7. When the baffle is rotated in counterclockwise direction, the arm 25 is moved to the left, and the movable slats 24 of the shutters A are moved to, or towards, their angular obstructing position, Fig. 8.

The baffle is actuated or adjusted by a mechanism such as that illustrated in Fig. 2, which includes a segment 44 carried by the baffle and a worm 45 carried by a shaft 46. The shaft 46 is turned by means of a wheel 47. Due to the height of the machine, the wheel 47 is in the nature of a pulley or sprocket over which passes a belt or chain 48, which also engages a handwheel 49 accessible to an operator attending the machine. An index 50 cooperates with a graduated dial 51 to indicate the position to which the baffle is adjusted.

In order to minimize the force needed to adjust the baffle and the shutters A, the weight of the baffle, in relation to the weight of the movable slats of the shutters A, and the linkage connecting the baffle to these slats are such that the parts are in substantial balance so that, in turning the handwheel 49, the operator need exert only enough force to overcome the inertia and friction present.

The set of shutters B are, except for not being connected to the baffle, identical with the shutters A and are adjusted by a mechanism such as that shown in Fig. 5, which includes a segment 44x carried by the arm 25 and engaging a worm 45x on a shaft 46x. The shaft 46x, like the shaft 46, is provided with a sprocket or pulley 47x over which passes a belt or a chain 48x which also engages a lower handwheel, not shown, which corresponds to the wheel 49.

In order to facilitate operation of the shutters B, I provide a tension spring 54, one end of which is connected to the left-hand end of the bar 25 of the shutters B and the other end of which is anchored to the framework of the machine, as at 55. The spring 54 tends to move the bar 25 to the left, or in a direction to move the slats 24 of the shutters B towards their obstructing position, Fig. 8. The strength of the spring 54 is, however, so related to the weight of the movable slats 24 of the shutters B that the parts are normally in balance. Therefore, to adjust the shutters B, the operator need only exert force sufficient to overcome the inertia and friction present.

In operation, the air delivered by the blowers 28 tends to rush into the distal portion of the air-receiving space 31, so that the distal piece of goods 14 tends to receive a greater supply of air, and will, other things being equal, dry at a faster rate than the piece 13. While the slanting roof 58 of the air space 31 helps to correct this situation and may produce satisfactory results under certain conditions, I have found that under other conditions, it does not. For example, the moisture content, the thickness, texture, or nature of the moisture content of the pieces 13 and 14 may vary considerably in actual practice and, therefore, additional control and regulation of the flow of air has been found to be necessary. To this end, I have provided the baffle 34 and the means for moving the slats 24 of the set of shutters A concomitantly with the movement of the baffle to increase or decrease the amount of air blown down over the piece 13, while independently adjusting the set of shutters B, as may be indicated. Thus, if it is desired to increase the flow of air to the piece of goods 13, the baffle is moved to, or towards, the position shown in solid lines in Fig. 6. This obstructs the flow of air to the portion of the air space 31 to the right of the baffle, or the portion thereof above the piece 14. By adjusting the shutters B toward their closed position, the amount of air reaching the piece 14 is further decreased and the amount reaching the piece 13 will be increased accordingly. The reverse movement of these parts reverses the result.

The moisture in the pieces 13 and 14 tends to gravitate towards the bottom portions of the loops and, since the bottom portions of the loops are further removed from the source of heated air, it is found that the upper and lower portions of these loops do not dry uniformly. To remedy this condition, I have positioned the heating media, such as steam coils 29 directly below the

false floor 27 so as to subject the lower portions of the loops to radiant heat, and also to compensate for the drop in the temperature of the air in the region of the lower portions of the loops.

In order to increase the efficiency of the blowers 28, I have spaced them from the steam coils. As best shown in Fig. 3, the blowers 28 are located in a compartment 60, extending along the drying chamber, and connected to the steam coil chamber 33 by means of the opening 32. By this arrangement, the air is drawn through the fan at a relatively lower velocity than it would be if the steam coils were located immediately adjacent the intake side of the blowers, thus reducing the friction factor. Also, by this arrangement, the air called for by the blowers will be drawn from over the entire area of the heating coils instead of from a limited area thereof which would be the case if the heating coils were placed immediately adjacent the intake side of the fan. Furthermore, the spacing of the blowers from the heating coils causes the air to flow from the heating coil compartment 33 to the intake side of the fan without eddying.

It will also be noted that the propellers of the blowers 28 are well spaced from the slanted roof 62 of the blower compartment 60 and the opening 30 leading to the air-receiving chamber 31. By this arrangement, the dynamic pressure of the air stream is changed to static pressure, thus eliminating eddying and turbulence of the air in the air-receiving space 31.

It will thus be seen that, by my construction, the flow of air over the pieces of sheet material 13 and 14 can be accurately regulated uniformly to dry both pieces; that the lower portions of the loops are subjected to radiant heat so as to compensate for the drop in the temperature of the air to which these lower portions of the loops are subjected; that the efficiency of the blowers is increased; and that flow of air from the discharge side of the blowers to the air-receiving space above the material to be dried is also improved.

The blowers 28 are mounted on vertical shafts disposed in the compartment 60 and the motors thereof are shielded from the hot air by suitable means 64. This disposition of the blowers is advantageous in that the air inlet 30 leading to the air receiving compartment 31 and the outlet 32 leading from the heating compartment 33 are both wholly unobstructed and the blades of the blowers are sufficiently remote from said inlet and outlet so as to improve the efficiency of the blowers as above set forth.

The lower heating compartment 33 is substantially coextensive with the underside of the drying chamber thus affording ample space for adequate dispersal of the heating coils so as to permit the air called for by the blowers to come into contact with the entire surface of the heating coils at a relatively low velocity. This increases the heat exchange between the coils and the air. Also the ample space in the compartment 33 provides the desired volume of air and since this air moves at a relatively low speed its friction factor is reduced and the efficiency of the blowers is increased.

In the operation of a drying machine of this type, lint, hair and other foreign matter is produced and tends to accumulate inside the machine, especially between and around the slats 23 and the heating coils 29. In order to prevent this condition a screen 66 is interposed between

the blowers and the material to be dried. As shown, the screen is placed between the false floor 27 and the heating coils 29 so as to catch and retain lint and other dirt which may be carried by the air stream.

In order to facilitate cleaning, the screen 66 is made flexible and is of a length slightly more than double the length of the drying chamber, with the opposite ends of the screen secured to rollers 67 and 68 disposed outside of the drying chamber and at opposite ends thereof. Each of the rollers is rotatable in a direction to pay out or to wind the screen. In operation, the roller 67, for example, is turned so as to wind the portion of the screen in excess of the length of the drying chamber, thus leaving the other portion of the screen stretched under the drying chamber. After the machine has been in operation for some time, the roller 68 is turned in a direction to wind the screen thereon, and as the screen emerges from the drying chamber, or the heating compartment, it is subjected to the action of manual or automatic, mechanical or pneumatic cleansing means such as a brush or a suction cleaner. As the screen winds on the roller 68, the clean section thereof which was wound on the roller 67 is stretched under the drying chamber and the section thereof previously under the drying chamber is cleaned and wound on the roller 67 for future use.

30 What I claim is:

1. The combination with a drying machine including a structure defining a drying chamber adapted to receive two separate materials to be dried simultaneously, a wall structure defining a compartment having an inlet for admitting a fluid-drying medium, there being a first set of passages leading from said compartment to said chamber for directing a portion of said drying medium towards one of said materials, and a second set of passages for directing another portion of said drying medium towards the other of said materials, and means for delivering a fluid-drying medium under pressure to said compartment, there being exhaust openings leading from said chamber, of control means for regulating the flow of said drying medium to said material, said control means including a first set of shutters for obstructing or non-obstructing said first set of passages, a baffle connected to, and movable jointly with said first set of shutters, means for jointly actuating said first set of shutters and said baffle, said baffle being so arranged that when said first set of shutters are moved towards their non-obstructing position said baffle moves towards a position in which it partly obstructs the flow of said fluid-drying medium from said inlet to said second set of passages and vice versa, and means for actuating said second set of shutters towards their obstructing or non-obstructing positions independently of said first set of shutters and said baffle.

2. The structure recited in claim 1 in which said first set of passages is adjacent the inlet end of said compartment and said second set of passages is remote from said inlet.

3. The structure recited in claim 1 in which said baffle is so related and connected to said first set of shutters that said baffle and said shutters substantially counterbalance each other in any position to which they are adjusted.

4. The structure recited in claim 1 in which said baffle is located intermediate said first and

shutters are pivoted for rotation about parallel horizontal axes.

5. The structure recited in claim 1 together with means for counterbalancing at least a major portion of the weight of said second set of shutters.
